UNITED STATES PATENT OFFICE

JAMES J. REGAN, OF LOS ANGELES, CALIFORNIA

(ANTIFRICTION) TRAVELING BLOCK

Application filed March 1, 1929. Serial No. 343,608.

This invention relates to an improved traveling-block for oil-well elevators wherein simplicity, strength and low cost of manufacture are among the desirable advantages secured.

Another object of the invention is to provide improved bearings which are furnished with dependable means for keeping them properly lubricated.

10 Other objects and advantages may hereinafter appear.

Referring to the accompanying drawings which illustrate what is at present deemed to be a preferred embodiment of the invention.

15 Fig. 1 is a side view of the complete device shown partly in section and partly in elevation.

Fig. 2 is an edge elevation part of one of the pulleys being broken away to contact the 20 view.

Fig. 3 is an elevation of a modification.

Referring in detail to the drawings, a composite crown-block and pulley-block construction is shown which comprises the side plates 25 1, the upper handle 2 and lower handle 3. The internal portion of the frame comprises the vertical parallel bars 5 which are preferably equal in length and which are secured together in spaced relation to each other by 30 means of the pulley-shafts 6, 7 and 8 in conjunction with the spacing sleeves 9, said shafts each having threaded extremities which extend beyond the sides of the frame and have screwed on to them the nuts 11, 12 and 13 whereby clamping means are provided to secure the frame parts in place.

35 The side plates 1 are provided with feet 1^a having apertures 1^b to receive attaching means for securing them to any suitable support such as the I-beam 1^c.

Between the upright frame bars 5 are mounted upon the various shafts 6, 7 and 8 the traction pulleys one of which, designated 15, is shown in the drawings, being mounted 45 on the shaft 7.

The shoulder 1^s on each side plate 1 underlies the lower end of the adjacent outer frame bar 5 and thus adds to the stability of the supporting means.

50 In order to afford dependable means for

lubricating the various pulleys, the shaft 7 is provided with an oil passage or reservoir 25 from which the radial oil-feeding branches 26 lead, said passage being closed at its ends by screw plugs 25^a each of which communicates with an oil pressure feed device 25^b. Each of its radial branches 26 registers with a duct or port 27 through the adjacent spacing sleeve 9. In order to keep the various spacing sleeves in their correct circumferential positions a plurality of short spline grooves 28 are provided in shaft 7 and in these grooves are seated the spline key pins 29. Said key pins are positioned, as shown in Fig. 1, with the greater portion of their lengths alining with the frame bars 5, their ends projecting laterally beyond said bars and engaging internal grooves or recesses in the spacing sleeves 9 to keep said sleeves from turning and to hold them with their oil ports 27 in register with the radial oil ducts 26.

Each traction pulley 15 is provided with roller bearings 15^b which are interposed between hub 15^a of the wheel and the particular spacing sleeve 9 upon which it is mounted. The wheel hub 15^a has secured to it the side plates 15^c by means of screw bolts 15^d. These plates enclose the roller bearings 15^b. The upwardly directed arrow, near the right side of Fig. 1, indicates the direction in which force is applied to shaft 7.

The handle 2 is secured to shaft 6 and the handle 3 is secured to the shaft 8. Each of these handles is of a U-shaped form and has its limbs provided with alined apertures and handle 3 has roller bearings 33 to eliminate friction between it and the shaft upon which it is mounted.

In Fig. 3 is shown a modification wherein 90 is illustrated a pulley block having a pulley shaft 50 with which is combined the two upright side plates 51 and the two intermediate spacer plates 52. Said side plates 51 have their lower ends bolted to opposite sides of the pedestal 55 which is supported upon a base 55^b, and their upper ends bolted to opposite sides of a head piece 56. Otherwise the pulleys 57 are mounted in the same manner as the pulleys which have been previously described. 95 100

The base flange 55^t of the pedestal 55 stabilizes the supporting means for the outer side plates 51, thus performing a function which corresponds to that of the shoulder 1^s of Figs. 1 and 2.

5 Claims:

1. In a device of the character described, a frame comprising a plurality of parallel bars, said bars having a series of alined openings, a shaft fitted within said openings and extending from side to side of said frame, a spacing sleeve around each section of the shaft which is located between adjacent bars of said frame, clamping means engaging the 10 end portions of said shaft to clamp said bars against the ends of said sleeves, said shaft being provided with splines which underlie said sleeves and bars, said shaft being provided with an oil supply and with radial oil feeding 15 passages leading therefrom, said sleeves having ducts adapted to register with said oil feeding passages, and key pins seated in said spline opposite said bars and having end portions projecting beyond the sides of said bars 20 to keep in register with each other the radial oil passages of said shaft and the oil ducts of said sleeves.

2. In a device of the character described, a frame comprising a plurality of parallel bars 30 which extend longitudinally thereof, said bars having a plurality of alined shaft openings which are located along a line that is intermediate the end portions of said bars, a bearing shaft extending through and fitted 35 within said alined openings, combined bearing and spacing sleeves fitted to said shaft and located between said bars, clamping means secured to said shaft to clamp said shaft bars and sleeves together, and combined 40 leg and side plate at each end of said frame to complete and stabilize the same, said combined leg and side plate overlying the adjacent bar of said parallel bars and having a shoulder which abuts against the end thereof, said combined leg and side plate being included within said clamping means.

In testimony whereof I hereunto affix my signature.

JAMES J. REGAN.
